Primary Examiner—James Gandy**Assistant Examiner—Cathron B. Matta****[57] CLAIM**

The ornamental design for a squeeze and turn child resistant closure, as shown and described.

DESCRIPTION

FIG. 1 is a perspective view of the squeeze and turn child resistant closure showing my novel design;

FIG. 2 is a top plan view;

FIG. 3 is a side elevational view taken from the bottom in FIG. 2, the left side view being the mirror image thereof;

FIG. 4 is a view taken from the right in FIG. 3, the left side view being the mirror image thereof;

FIG. 5 is a perspective view of a modified squeeze and turn child resistant closure;

FIG. 6 is a top plan view;

FIG. 7 is a side elevational view taken from the bottom in FIG. 6, the left side view being the mirror image thereof; and,

FIG. 8 is a view taken from the right in FIG. 7, the left side view being the mirror image thereof.
